UNITED STATES PATENT OFFICE

SAMUEL A. SPENCER, OF DENVER, COLORADO

VENTILATOR

Application filed February 18, 1930. Serial No. 429,295.

An object of this invention is to provide an improved ventilator.

A further object of the invention is to provide an improved exhausting nozzle for ventilating ducts.

A further object of the invention is to provide improved means for inducing draft in ventilating ducts, chimneys and the like.

A further object of the invention is to provide an improved construction of a draft-inducing duct terminal.

A further object of the invention is to provide improved means for utilizing normal air currents at the exhaust end of a duct to induce an air flow through said duct.

A further object of the invention is to provide an improved construction of a draft-inducing duct terminal operable by normal air currents irrespective of their direction.

A further object of the invention is to provide an improved Venturi-type draft-inducing duct terminal.

A further object of the invention is to provide an improved construction of draft-inducing duct terminal whereby a one direction draft uniform throughout the cross sectional area of said duct is maintained through said duct.

A further object of the invention is to provide an improved device of the character hereinafter described which is simple and inexpensive of manufacture and installation, positive and efficient in operation and durable in use.

My invention consists in the construction, arrangement and combination of elements hereinafter set forth, pointed out in my claims and illustrated by the accompanying drawings, in which—

Figure 1 is a side elevation of one form of my improved ventilating nozzle. Figure 2 is a vertical section axially of the showing of Figure 1. Figure 3 is a cross section on the indicated line 3—3 of Figure 1. Figure 4 is a cross section on the indicated line 4—4 of Figure 1, portions of the outer shell being broken away to conserve space. Figure 5 is a side elevation of a modified form of improved ventilating nozzle. Figure 6 is a view similar to Figure 5, certain elements

being in section to better disclose interior construction.

The invention relates to draft-inducing nozzles adapted to be mounted on and in communication with the exhaust ends of 55 ventilating ducts, chimneys, and the like, in order to establish and maintain an air flow or circulation through said ducts or chimneys, for any purpose whatsoever, the improvement being likewise adapted for direct mounting 60 on buildings and enclosed structures in communication with the interiors thereof for the purpose of exhausting vitiated air and other gases from said interiors and ventilating said structures.

In the construction of my improvement as shown, the numeral 10 designates a hollow cylinder formed of any suitable material, such as sheet metal, in any desired manner, said cylinder being open at each end and 70 having a uniform, smooth bore for the free passage of air and other gases. A frustoconical shell 11 is formed of any suitable material and in any desired manner with an open base having a diameter substantially 75 one and one-half times that of the cylinder 10 and an open lesser end having a diameter approximately equal that of said cylinder, said shell 11 being positioned in axial alignment with the cylinder 10 and having its open 80 base in telescoping relation about and below the open upper end of said cylinder, means hereinafter to be described securing the cylinder 10 and shell 11 in the relation specified and positioning the lesser end of 85 said shell in spaced, registering relation with the upper end of said cylinder. A plurality of similar vanes 12, in this instance four in number, is mounted within and extends throughout the length of the shell 11, each 90 of said vanes being concavo-convex in cross section throughout its length and tapered along its outer margin to conform with the taper of the said shell 11, said vanes being spaced apart uniformly on the inner surface 95 of the shell 11 with the convex surface of one vane opposed to the concave surface of its adjacent vane, each of said vanes being secured along its tapered outer margin to the interior of the shell 11 in such manner as to 100

permit each vane to make substantially one-eighth of a revolution between its point of attachment at the base of said shell and its point of attachment at the top of the shell 5 and forming ascending spirals of said transversely curved vanes within and extending throughout the length of said shell. The inner margins of the vanes 12 are brought together on the axis of the shell 11 and firmly secured to one another by means of bolts or rivets 13 adjacent the upper and lower ends of said vanes, mid-portions of said vanes being notched out as shown at 14 to provide a common mixing chamber through which 10 communication may be had between the different compartments of the shell 11 defined by the vanes 12. The lower end of each vane 12 is notched to receive the upper end 15 of the cylinder 10, and said vanes 12 extend 20 in a smooth curve below the lower end of the shell 11 a distance substantially equal to the spacing between the lower circumference of said shell and the outer surface of the said cylinder to terminate in ears 15 fitting snugly 25 against and rigidly secured to said cylinder, thus securely supporting the cylinder 10 from and in the desired relation with the shell 11, or vice versa.

In the modification according to Figures 30 5 and 6, the construction and relation of the elements 10, 11 and 12 is in all respects identical with that above described, and, in addition, straps 16 are fixed to and rise in parallel relation perpendicularly from the upper 35 end of the shell 11 to support a relatively flat, conical cap 17 in spaced relation with and above the upper end of said shell. The cap 17 has an open base substantially equaling in diameter the base of the shell 11 and a closed 40 apex, which latter may be finished with an ornamental device such as a finial 18, as shown, and said cap is positioned on and secured to the straps 16 in axial alinement with the cylinder 10 and shell 11. In addition to the 45 cap 17, an annular, inclined vane 19 is interposed on the straps 16 between said cap and the upper end of the shell 11 and secured to said straps by means of integral ears 20 formed on the inner margin of said vane, said 50 vane taking the form of a hollow, truncated cone of low altitude and being open at both ends.

In the practical operation of my improvement, the elements being assembled and arranged as above described, the cylinder 10 is mounted in axially perpendicular position with its lower end communicating with a ventilating duct, chimney or an interior, in such manner as to positon the shell 11 in the 55 path of exterior air currents. When so mounted, any air current about the cylinder 10 will impinge on one of the projecting lower ends of the vanes 12 and be deflected upward along the concave surface of said 60 vane and into the interior of the shell 11, the

angle of the vanes 12 cooperating with their transverse curvature to impart a spiral or swirling motion to the incoming air and enhancing its velocity. Regardless of the direction of the exterior air currents, the air 70 entering the shell 11 from below may and does escape from a given compartment through the notched mid-portions of the vanes 12 to fill all of the compartments within said shell with air under uniform pressure; the ascending spiral effect of the vane arrangement being again useful to prevent the formation of downward air currents or eddies that might create a down pressure on the upper end of the cylinder 10. The shell 80 11 being filled with air taken in through its base, said air naturally tends to rise through and escape from the upper end of the shell by virtue of the spiral arrangement of the vanes 12 and the tapered form of the shell, 85 and this tendency is augmented by the suction effect of air currents passing across said upper end and by the upward air eddies resulting from currents impinging on the outer surface of the shell 11 from whence they are deflected upwards, all of which combines to induce an upward suction effect augmenting the Venturi effect of the shell and vane arrangement, thus inducing an upward flow of air through the cylinder 10 and exhausting 90 air and other gases from the duct, chimney or interior with which said cylinder is operatively connected. It is obvious that the modified construction shown in Figures 5 and 6 will function essentially as above described, the cap 17 and annular vane 19 serving to entirely eliminate any possible down pressure in the shell 11 due to exterior air currents and modifying the violence of the suction induced by air currents passing across the upper end of said shell, thus insuring a moderate, steady, upward flow through the cylinder 10 and providing an exhaust nozzle particularly adapted for use with ventilating systems, said cap 17 likewise serving as a 100 baffle to limit the upward flow of air through said cylinder and prevent erratic operation of the nozzle in air currents of varying intensity.

Since many changes and modifications in the specific form, construction and arrangement of the elements of my improvement may be had without departing from the principle and spirit of the invention, I wish to be understood as being limited solely by the scope 110 of the appended claims rather than by the illustrative showing and foregoing description.

I claim as my invention—

1. An air exhaust nozzle comprising a 125 cylindrical duct open at each end, a frusto-conical sleeve in axial alinement with said duct, said sleeve having an open base of greater diameter than said duct and in spaced, telescoping relation with one end 130

thereof, and spiral vanes axially of said sleeve and engaging said duct and sleeve, portions of said vanes meeting on the axis of said sleeve above said duct.

5. An air exhaust nozzle comprising a cylindrical duct open at each end, a frusto-conical sleeve in axial alinement with said duct, said sleeve having an open base of greater diameter than said duct and in spaced, telescoping relation with one end thereof, spiral vanes within said sleeve and meeting on the axis thereof to divide said sleeve into uniform compartments and means on the ends of said vanes engaging said duct 10 whereby said sleeve is positioned on and supported by said duct.

20. An air exhaust nozzle comprising a cylindrical duct open at each end, a frusto-conical sleeve formed with an open base of greater diameter than said duct and mounted in axial alinement with said duct with said base in spaced, telescoping relation therewith, transversely-curved, spiral vanes within said sleeve and meeting on the axis 25 thereof to divide said sleeve into uniform compartments and extensions on said vanes engaging said duct whereby said sleeve is positioned on and supported by said duct.

30. An air exhaust nozzle comprising a cylindrical duct open at each end, a frusto-conical sleeve formed with an open base of greater diameter than said duct and mounted in axial alinement therewith with said base in spaced, telescoping relation with one end thereof, transversely-curved, spiral vanes within said sleeve and meeting on the axis thereof to divide said sleeve into uniform compartments, notches in the meeting edges of said vanes whereby a mixing chamber is 35 formed centrally of said sleeve and extensions on said vanes engaging said duct whereby said sleeve is positioned on and supported by said duct.

40. An air exhaust nozzle comprising a cylindrical duct open at each end, a frusto-conical sleeve in axial alinement with said duct, said sleeve having a base of greater diameter than said duct and in spaced, telescoping relation with one end thereof, transversely-curved spiral vanes within said sleeve and meeting on the axis thereof to divide said sleeve into uniform compartments, notches in the meeting edges of said vanes whereby a mixing chamber is formed centrally of said sleeve, extensions on said vanes engaging said duct to position and support said sleeve relative to said duct, spaced risers on the lesser end of said sleeve, a hollow conical cap supported by said risers in axial alinement with said sleeve 45 and spaced relation with the lesser end thereof and an annular, inclined vane supported by said risers between said cap and the lesser end of said sleeve.

55. In combination with an air duct having an open upper end, a frusto-conical sleeve

formed with an open base of greater diameter than said sleeve mounted on and rising from said duct in axial alinement therewith and with said base in spaced, telescoping relation with the open end of said duct, transversely-curved, spiral vanes within said sleeve and meeting on the axis thereof to divide said sleeve into uniform compartments, notches in the meeting edges of said vanes whereby a mixing chamber is formed centrally of said sleeve, extensions on said vanes below said sleeve and engaging said duct to position and support the former from and relative to the latter and inclined baffles carried by and in spaced relation with the lesser end of said sleeve.

7. The combination with an air duct having an open upper end of draft-inducing means carried by the open end of said duct, said means comprising a frusto-conical sleeve in axial alinement with and rising from said duct, said sleeve being formed with an open base of greater diameter than said duct in spaced, telescoping relation therewith, transversely-curved, spiral vanes within said sleeve and meeting on the axis thereof to divide said sleeve into uniform compartments, notches in the meeting edges of said vanes whereby a mixing chamber is formed centrally of said sleeve and extensions on said vanes below said sleeve and engaging said duct to support and position the former from and relative to the latter.

8. The combination with an air duct having an open upper end of draft-inducing means carried by the open end of said duct, said means comprising a frusto-conical sleeve in axial alinement with and rising from said duct, said sleeve being formed with an open base of greater diameter than said duct in spaced, telescoping relation therewith, transversely-curved, spiral vanes within said sleeve and meeting on the axis thereof to divide said sleeve into uniform compartments, notches in the meeting edges of said vanes whereby a mixing chamber is formed centrally of said sleeve, extensions on said vanes below said sleeve and engaging said duct to support and position the former from and relative to the latter and inclined baffles carried by and in spaced relation with the lesser end of said sleeve.

9. In a device of the character described, an air duct having an open upper end, an upwardly-tapered sleeve formed with an open base of greater diameter than said duct and rising from said duct in axial alinement therewith with said base in spaced, telescoping relation with the open end of said duct, transversely-curved vanes spirally positioned within said sleeve and meeting on the axis thereof to divide said sleeve into uniform compartments, said vanes extending below said sleeve and engaging said duct to support and position the former from and relative to the

latter, notches in the meeting edges of said vanes whereby a mixing chamber is formed centrally of said sleeve, a frusto-conical cap in axial alinement with and spaced above the lesser end of said sleeve and an inclined, annular vane between and spaced from said cap and the lesser end of said sleeve.

Signed at Denver, in the county of Denver and State of Colorado, this 2nd day of

October, 1929.

SAMUEL A. SPENCER.
